August Goertz.

BY Drake & Co. ATTYS.

UNITED STATES PATENT OFFICE.

AUGUST GOERTZ, OF NEWARK, NEW JERSEY.

FASTENING FOR SATCHEL AND POCKET-BOOK FRAMES.

SPECIFICATION forming part of Letters Patent No. 352,687, dated November 16, 1886.

Application filed June 28, 1886. Serial No. 206,493. (No model.)

To all whom it may concern:

Be it known that I, AUGUST GOERTZ, a citizen of the United States, residing at Newark, in the county of Essex and State of New Jersey, have invented certain new and useful Improvements in Pocket-Book and other Bag Frames; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention relates more particularly to certain improvements in fastenings for that class of bag, purse, or satchel frames in which the catch is arranged in a recess formed at the center of said frame between the separated 20 ends of the strengthening ribs or beads formed longitudinally thereon.

25 The invention consists in the arrangements and combinations of parts, substantially as will be hereinafter set forth, and finally embodied in the clauses of the claim.

30 Referring to the accompanying drawings, in which like letters indicate corresponding parts in each of the several figures, Figure 1 is a plan of the frame; Figs. 2 and 3, cross-sections thereof taken centrally through the catch, the first showing the catch in fastening engagement and the second showing the catch uplifted to allow a separation of the frame-sections; and Fig. 4 is a detail perspective view 35 of the catch, showing the under side thereof.

40 In said drawings, *a a* indicate the ordinary hinged sections of the frame, provided with tubular strengthening-ribs *a' a'*, which extend along the top of the frame and are separated at the center, forming recesses in which the catch *b* has its bearings. Said catch is actuated to hold the sections together by a spring, *b'*, in about the manner described in an application filed contemporaneously herewith, and 45 numbered serially 206,492. In said contemporaneous application a catch is shown having certain eccentric projections extending in a direction opposite to the finger projection herein shown to engage the side or top of the

frame and limit the movement of the catch. 50 This stop or limiting projection, in that it extends beyond the line of the frame, is by some buyers in the market considered in a degree unsightly and tends to render the frame bulky; and, again, when it is of considerable size and 55 of a shape similar to the finger projection, tends to confuse the person opening the purse. To avoid its use and the objections arising therefrom and yet retain the advantages of a stop, I have formed on the frame at a point beneath the catch an upwardly-projecting teat or lug, *c*, and in the bottom of the catch a slot or recess, *b'*, into which the projection or lug *c* extends, the slot allowing requisite movement of the catch. The notch *b'* engages the 60 co-operating catch *d*, formed on the adjacent frame-section in the ordinary manner. By the construction described the limiting mechanism is hidden or nearly hidden from view.

Changes may be made in the device by providing equivalent parts for those described without departing from or avoiding the scope 65 of this invention.

I am aware that in the patent of Prahar, No. 339,577, a frame is shown and described having a spring-latch similar in arrangement to the catch *b*, herein specified, but having a rearwardly-extending flange adapted to come in contact with the side of the frame to limit its scope or movement. In the improved device 80 the use of this flange is avoided for reasons already given, and the mechanism for limiting the movement of said catch is sufficiently concealed, so as not to be objectionable.

What I claim as new is—

The combination, with the hinged sections, one of which is provided with a limiting projection and the other with a co-operating catch, of a catch, *b*, provided with a slot or recess, *b'*, on its under side, into which said projection extends, substantially as set forth.

In testimony that I claim the foregoing I have hereunto set my hand this 17th day of June, 1886.

AUGUST GOERTZ.
